(57) **CLAIM**

The ornamental design for a wearable temperature measurement device, as shown and described.

DESCRIPTION

FIG. 1 is a perspective view of a wearable temperature measurement device embodying our new design;

FIG. 2 is top view thereof;

FIG. 3 is a front view thereof;

FIG. 4 is a back view thereof;

FIG. 5 is a side view thereof; and,

FIG. 6 is another side view thereof.

Broken lines, where shown, are used to illustrate portions of the wearable temperature measurement device or environmental subject matter that form no part of the claimed design.
